Attorney.

UNITED STATES PATENT OFFICE.

JOHN EDGAR RICHMOND, OF EUGENE, OREGON.

TOOTH CROWN.

Application filed March 8, 1921. Serial No. 450,660.

To all whom it may concern:

Be it known that I, JOHN E. RICHMOND, a citizen of the United States, residing at Eugene, in the county of Lane and State of Oregon, have invented certain new and useful Improvements in Tooth Crowns, of which the following is a specification.

This invention relates to porcelain tooth crowns as used by dentists; and it consists in a crown provided with a liner as herein-after fully described and claimed, and in the method of making and applying the same.

In the drawings, Figure 1 is vertical section through a tooth provided with a crown and liner according to this invention. Fig. 2 is a side view of the tooth, prepared to receive the crown. Fig. 3 is a vertical section through the porcelain crown, and Fig. 4 is a front view of it. Fig. 5 is a vertical section through the liner.

A porcelain crown can be secured on a tooth, according to this invention, without devitalizing the tooth, and without removing its nerve or pulp. The tooth 7, in the jaw 25 of the patient, which requires to be repaired, is prepared as shown in Figs. 1 and 2, by first removing the enamel and as much of the dentine as necessary to form a conical stump 8 without any undercuts. A square shoulder 30 9 is cut around the neck of the tooth, following the gum line, to form a definite base for the porcelain crown and its liner. The porcelain crowns 10 are made in quantities, and in standard shapes and sizes, of porcelain or other similar material. The chamber 35 12 in the crown is made conical, with one diameter slightly greater than the other, or it is otherwise formed, so that the crown will not revolve with relation to the tooth.

The tooth being prepared as hereinbefore described, a porcelain crown is selected of suitable size, shape and color, and having a chamber 12 which will fit very loosely over the stump 8. The base of this crown and 45 the shoulder 9 on the tooth are fitted together, so that the crown fits smoothly on the shoulder on the tooth and forms a good joint. The porcelain crown is then removed from the stump and the interior of the

chamber 12 and the surface of the stump are 50 moistened with water, oil, or other lubricant which will prevent wax from adhering to them.

The porcelain crown is then warmed, and a small quantity of inlay wax is softened by 55 heat and is placed in the chamber, and the crown is then pressed over the stump. If the crown does not fit nicely on the stump and its shoulder, it is removed and warmed slightly, so as to soften the wax without 60 melting it, and the crown is again pressed over the stump. When the crown fits nicely on the stump, it is cooled to harden the wax. When the wax is hard enough the porcelain crown is slipped off the wax, and the wax 65 liner model is in turn removed from the stump, taking care not to distort it. A sprue wire is then attached to the wax model, and the model is invested, burned out, and cast with any suitable metal, in the same way as 70 an ordinary cast gold inlay.

A metal liner 14 is thus formed, which, when the sprue is cut off, and the liner properly finished and polished, will fit smoothly into the chamber of the crown and onto the 75 stump of the tooth. The stump, liner and crown are then secured together by any suitable cement, and the crown will then give approximately the same appearance and service as a natural tooth.

The crowns are made of porcelain, or other material of tooth color, in commercial quantities with the interiors of the crowns ground to definite shapes and sizes so as to make them, within certain limits, interchangeable. The liners, adapters, or bushes are made by the dentists, who do not manufacture the porcelain crowns, but who prepare the teeth, and fit the crowns to them by means of the liners, adapters or bushes as 85 90 hereinbefore described.

What I claim is:

1. A porcelain tooth crown provided with a chamber, and a metal liner for the said chamber secured therein and formed of a 95 single piece of cast metal which fits closely in the said chamber and is adapted to fit closely over a tooth stump, said metal liner

having been reproduced from a wax model formed in the space between the selected hollow crown and a stump formed on the tooth of the patient above the gum line.

5 2. The method of securing a hollow porcelain crown to a tooth, which consists in first forming a stump on the tooth above its gum line, then forming a wax liner model in the

space between the stump and the hollow crown, then reproducing the said model in 10 metal, and finally cementing the metal liner into the crown and onto the said stump.

In testimony whereof I have affixed my signature.

JOHN EDGAR RICHMOND.
